UNITED STATES PATENT OFFICE

LOUIS E. SOMERS, OF DETROIT, MICHIGAN, ASSIGNOR TO THE W. H. KRATZER COMPANY, OF DETROIT, MICHIGAN, A CORPORATION OF MICHIGAN

DEVICE FOR CLEANING FURNACES

Application filed March 22, 1928. Serial No. 263,845.

This invention relates to a suction furnace cleaner and has for its object the production of a device that is inexpensive to manufacture and efficient in operation.

Another object of this invention is to provide a device that can be readily dismantled in order that the device may be taken in close proximity to the pipe that is being cleaned.

Another object of the invention is to provide a device of this type that is easy to clean and may be operated even though part of it is fractured and which is capable of compact and unified arrangement in an inoperative condition, for convenient movement from place to place.

These and other objects are attained by the means described herein and disclosed in the accompanying drawings, in which:

Fig. 1 is a front elevation of a device of this invention, showing the device in a compact position.

Fig. 2 is a front elevation of the device in an operative position, part of the device being shown in cross section.

Fig. 3 is a sectional view taken on line 3—3 of Fig. 2.

Fig. 4 is a sectional view taken on line 4—4 of Fig. 1.

Fig. 5 is a sectional view taken on line 5—5 of Fig. 2.

Fig. 6 is a sectional view taken on line 6—6 of Fig. 2.

Fig. 7 is a fragmental perspective view of the suction hose and cap, forming details of the invention.

The furnace cleaner comprises a casing 10 having a front wall 11 and a base 12. The casing 10 is reinforced at its corners by angle irons 13 and 14. The angle irons 14 secured 40 at the base of the casing 10 support the bottom 12 upon which a dirt box 15 rests.

The dirt box 15 is provided with a plurality of perforations having upstanding flanges 16 to which are attached air release bags 17.

45 The bags 17 are adapted to lie collapsed upon the top of box 15 when the device is not in operation. The bags 17 have a closed top 18 and are secured to the flanges 16 by removable rubber bands 19. One of the flanges 16, 50 shown at 20, has secured to it a bag 21, simi-

lar to the bags 17, but having its upper end open for receiving the discharge spout 22 of the inlet pipe 23. The end 220 of the bag 21 is secured to the inlet pipe 23 by means of a removable rubber or tapered metal band 24.

55 The inlet pipe 23 communicates with the interior 25 of a fan housing 26. Interiorly of the fan housing is disposed a fan 27 having reversible plates 28. The fan 27 is carried by the motor shaft 29 of a motor 30. The housing 26 is provided in its one face with a flange 31 and in its other face with an opening 32 through which opening the motor shaft 29 extends. The flange 31 receives a cap 33 which has extending from it a hose connection 34 for receiving one end of a hose 35.

60 The motor 30 is mounted on a platform 36 carried by brackets 37. The motor and fan housing 26 are mounted within an open frame work 38 which comprises suitable angle irons 39 and connecting bars 40. This open frame work containing the motor and the encased fan is so proportioned in relation to casing 10 that it can be lowered into the latter for 65 compactness and convenience in moving the device from one place of operation to another.

70 The angle bars secured at the upper end of the casing 10 carry hinges 41. One leaf of each hinge 41 has a Z-shaped cross section as shown at 42. When it is desired to operate the cleaner the frame 38 is removed from the casing 10 and the hinge members actuated to the interior of the said casing 10. One arm 43 of the hinge leaf 42 forms a seat upon which the frame 38 rests for supporting the 75 motor and fan above the casing. This is clearly illustrated in Fig. 2.

75 In order to give access for connecting the end 220 of the bag 21 to the inlet pipe 23 after the frame has been mounted in the position shown in Fig. 2, a door 44 has been provided in the front wall 11 of the casing 10. This door reciprocates in opposed ways 45 formed in the front wall 11 by bending the said wall upon itself as shown at 46.

90 The operation of the device is as follows: The device is carried or shipped to the job in a compact condition, such as is shown in Fig. 1, then placed adjacent the furnace to be cleaned whereupon the frame 38 together 95

with motor 30 and fan 26 are lifted out of the casing and the hinge members 42 actuated toward the interior of the casing. The frame is now set upon the supports 43 in the position shown in Fig. 2. The door 44 is opened so that the end 220 of the bag 21 can be mounted on the intake pipe 23. The cap 33 is mounted upon the flange 31, the door slipped back into position, and the motor started for causing a suction through the pipe 35. The end 47 of the hose 35 is now placed within the smoke compartment or chamber of a furnace and the dirt and soot is drawn through the pipe into the dirt box 15. The air which passes into the dirt box 15 is released through the air release bags 17 and any dirt that might be carried into these bags is held within the bags while the air is permitted to escape. It has been found that by using a plurality, for example, as shown in this case, 8 release bags, that it is possible to release the air twice as fast as compared with one bag occupying the same air space. It may be noted that the device can be used by two operators simultaneously, by supplying cap 33 with two hose connections instead of one. A further feature of the present invention is that the bags are independently operable, that is, should one or more of the bags 17 become torn or fractured the perforation with which it is associated may be suitably covered and operation of the device continued without interrupting work on a given job.

What is claimed is:

35 1. A suction furnace cleaner comprising an outer open-top casing, an open frame structure receivable in the casing, an encased fan and motor supported by and within said open frame structure, a dirt receiving box 40 within and at the base of the outer casing, said box having in its top face a plurality of openings with upwardly extending flanges; a plurality of tubular bags adapted to fit upon and be secured to said flanges at their 45 lower ends which are open, the opposite or upper ends of all but one being closed; an inlet pipe communicating at one end with the interior of the fan casing and adapted to be inserted in and have secured thereto at its opposite end the top of the aforesaid single bag with open upper end; a shaft connecting fan 50 and motor on one side of the fan casing, an outer flange surrounding an aperture on the opposite side of the casing and a hose adapted 55 to communicate with said flanged aperture and provided, for this purpose, with a cap to fit upon said flange.

2. A suction furnace cleaner consisting substantially of two co-operative, separable 60 parts, one an outer casing with a dirt-receiving box in its base and air-release bags removably attached and communicating therewith, and the other, an open frame structure positioned within the casing while the 65 device is inoperative, and adapted to seat

upon the top portion of the casing when the device is to be used, the open frame containing the motive and suction means, including a dust intake pipe that detachably communicates with the dirt box.

3. In a device of the class described, the combination of an outer casing, an open frame structure supporting operative parts of the device and receivable by the outer casing, and means whereby said frame structure is held within the top portion of the casing during operation of the device.

4. A furnace cleaning device comprising a casing, a frame structure receivable in the casing, a fan contained in a housing and a motor for driving the fan, the encased fan and motor being supported by and within the frame structure, a dirt reception chamber in the casing and in communication with the fan housing, a hose communicating with the interior of the fan housing, and a plurality of air release bags attached to and communicating with the dirt chamber and positioned in the casing.

5. In a furnace cleaning device the combination of a casing comprising a dirt chamber, collapsible air-release means on top of the chamber and within said casing, a frame 90 slidably within the casing, a suction and power means mounted within the frame and means on the casing for supporting the frame within the top portion of the casing.

In testimony whereof, I have hereunto subscribed my name this 7th day of March, 1928.

LOUIS E. SOMERS.
